UNITED STATES PATENT OFFICE.

CHARLES BOOZE, OF BUFFALO, NEW YORK, ASSIGNOR TO M. H. BIRGE & SONS, OF SAME PLACE.

DESIGN FOR WALL-PAPER.

SPECIFICATION forming part of Design No. 22,891, dated November 14, 1893.

Application filed October 7, 1893. Serial No. 487,512. Term of patent 3½ years.

To all whom it may concern:

Be it known that I, CHARLES BOOZE, a citizen of the United States, residing at Buffalo, in the county of Erie and State of New York, 5 have invented and produced a new and original Design for Wall-Paper of which the following is a specification.

The design consists of a series of heart-shaped ornaments formed of arabesque scrolls 10 and flowers arranged at regular distances apart over the surface of the paper as represented in the accompanying drawing. The border or upper portion of said design is formed of the same heart-shaped ornaments 15 connected by smaller ornaments of arabesque scrolls and flowers as shown, and a narrow ornamental band dividing the border portion from the hanging.

What I claim is—

1. The design for wall paper herein shown and described.

2. In the design for wall paper, the border herein shown and described.

Witness my hand this 2d day of October, 1893.

CHARLES BOOZE.
